J. L. DAHL.
STAKE POCKET.
APPLICATION FILED APR. 1, 1915.

1,160,143.

Patented Nov. 16, 1915.

Inventor:
John L. Dahl,
by *M. H. Anderson*,
Attorney.

UNITED STATES PATENT OFFICE.

JOHN L. DAHL, OF HACKENSACK, NEW JERSEY, ASSIGNEE TO THE GREGG COMPANY
LIMITED, OF HACKENSACK, NEW JERSEY, A CORPORATION OF NEW YORK.

STAKE-POCKET.

1,160,143.

Specification of Letters Patent. Patented Nov. 16, 1915.

Application filed April 1, 1915. Serial No. 12,534.

To all whom it may concern:

Be it known that I, JOHN L. DAHL, a citizen of the United States, residing at Hackensack, in the county of Bergen and State of New Jersey, have invented certain new and useful Improvements in Stake-Pockets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to stake pockets, and has for its object to provide a simple and efficient construction for securely holding or locking the swinging door of the pocket in its closed position and yet permitting it to be readily unlocked and swung upon its pivot or hinge when to be opened.

To the accomplishment of the foregoing and such other objects as may hereinafter appear the invention consists in the features hereinafter particularly described and then sought to be clearly defined by the claims, reference being had to the accompanying drawing forming a part hereof, and in

which—

Figure 1 is a perspective view of a stake pocket embodying the invention, and showing the door closed; Fig. 2 is a similar view, showing the door partially opened.

In the drawing the numeral 1 designates a box or pocket formed of suitable material and adapted to be bolted or otherwise secured to the side of a car to receive a stake which when in the pocket will rest on the bottom or shelf 2 of the pocket. To one side of the pocket is attached by a pin or bolt 3 a door 4 so as to swing on the bolt as the center of movement. The opposite end of the door is provided or formed with a shaft 5 adapted to move in and out of an open-faced socket or recess 6 formed in the opposite side wall of the pocket as the door is swung closed or open. This socket or recess is of different dimensions, for instance, its rear portion 7 is of larger dimensions than its front portion 8 so as to form a relatively restricted opening from the front into the rear or main portion of the socket for a purpose hereinafter indi-

cated. On the shaft 5 of the door is mounted so as to be rotatable thereon what will be designated for convenience and because of the function it performs, a cam 9, which in the form illustrated is oblong in cross section; and from this cam extends a handle or latch 10 by which the cam may be manipulated. When the door is to be closed or opened the cam is turned on its shaft so that its longest axis will be parallel or in alinement with the restricted opening 65 to the recess or socket 6 so as to permit it to be moved into or out of the recess or socket, and when the door is closed and is to be locked in that position, the longest axis of the cam will stand at or substantially 70 at right angles to the restricted opening into the socket, or transversely thereto, so that portions will lie above and below the restricted opening and thus lock the door in its closed position. By lifting or swinging 75 upward the latch or handle the cam may be brought into position to leave or enter the restricted opening to the socket or recess, and when the door is closed and the handle or latch released it will swing downward and carry the cam into locking position. For the purpose of securing the cam on the shaft 5 of the door a nut 11 may be fitted to the shaft and be held in position by a cotter-pin 12 passed through the shaft; 85 or if it be threaded onto the shaft then by screwing it up it will hold the cam in locking position.

I have illustrated and described the preferred details of construction of the several parts but they may be changed and essential features of the invention retained.

Having described the invention and set forth its merits, what I claim is—

1. A stake pocket having an open-faced socket or recess formed with a restricted opening in one side wall of the pocket, and a hinged door carrying a cam adapted in one position to pass through said restricted opening into the socket or recess and revolvable within the socket to close the restricted opening and hold the door in its closed position.

2. A stake pocket having an open-faced socket or recess formed with a restricted opening in one side wall of the pocket, and a hinged door carrying a revolvable oblong-shaped cam adapted in one position to pass

through said restricted opening and in another position to close said restricted opening and hold the door in its closed position.

3. A stake pocket having an open-faced socket or recess formed with a restricted opening in one side wall of the pocket, a hinged door provided at one end with a supporting shaft, a revolute cam supported by the shaft and shaped to pass through the restricted opening into the socket in one position and to close said opening in another position, and a latch or handle for operating the cam.

4. A stake pocket having an open-faced socket or recess formed with a restricted

opening in one side wall of the pocket, a hinged door provided at one end with a supporting shaft, a revolute cam supported by the shaft and shaped to pass through the restricted opening into the socket in one position and to close said opening in another position; a nut on the shaft to one side of the cam, and a handle or latch for operating the cam. 20

In testimony whereof I affix my signature 25
in presence of two witnesses.

JOHN L. DAHL.
